CARBURETOR

Grant Hammond, New Haven, Conn., assignor to
 The Hammond Company, New Haven, Conn.,
 a corporation of Connecticut

Application January 8, 1930. Serial No. 419,244

4 Claims. (Cl. 261—50)

My invention relates to the class of devices used for mixing air and an inflammable fluid, usually in the form of a liquid, for ignition purposes, and more particularly in connection with 5 internal combustion engines, and an object of my invention, among others, is the production of a device of this class that shall be extremely simple in construction and efficient in operation.

10 One form of a carburetor embodying my invention, and in the construction and use of which, the objects herein set out, as well as others, may be attained, is illustrated in the accompanying drawing, in which—

15 Figure 1 is a view in lengthwise central section through the shell and enclosed parts of my improved carburetor.

Figure 2 is a view in section on a plane denoted by the dotted line 2—2 of Figure 1.

20 Figure 3 is a detail view illustrating the spider for supporting the priming cup, this being in section on a plane denoted by the dotted line 3—3 of Figure 1.

In the accompanying drawing the numeral 3 25 denotes the shell of my improved carburetor that is preferably of generally cylindrical shape with an opening therethrough from end to end and with a flange 4 at one end to serve as a means for attachment of the shell to the manifold of an 30 engine or other part connected with said engine. A nipple 5 for the attachment of a fuel inlet tube is secured to and projects from one side of the shell, and a fuel inlet fixture 6 is preferably removably attached to the end of the nipple in- 35 side of the shell. This fixture is preferably of T-shape with the stem 7 screw threadedly engaged with the end of the nipple and having an inlet passage communicating with a passage through the nipple for the inflow of a combustible fluid. An inlet chamber 8 is formed in the cross piece 9 of the fixture 6, one end of said chamber being permanently closed and the opposite end thereof being partially closed by a flanged bushing 10 preferably screw threadedly 40 engaged with the mouth of the chamber 8 and with the flange of the bushing located against the end of the cross piece 9. The hole in the bushing is tapered and forms a seat for a needle valve 11 that is pressed against said seat as by 45 means of a spring 12 located in the inner end of the chamber 8.

A priming cup 13 is secured to the end of the needle valve 11, the mouth of said cup surrounding and receiving therein the end of the cross 55 piece 9, this cup being of a size to provide a little space between its wall and the outer surface of the ends of said cross piece for the outflow of fuel from the cup to the interior of the shell 3.

All of the parts thus far described form the 60 subject matter of a co-pending application filed

by me March 29, 1929, S. No. 351,019, which matured to Patent 1,890,782 issued Dec. 13, 1932 and to which reference is hereby made for a more complete understanding of the structure if such shall be desired, but the description herein given is sufficient for a thorough understanding of the invention forming the subject matter of this application. 65

A throttle valve 14 is pivotally mounted within the shell to close the opening at one end thereof, 70 this valve being supported as by means of a valve sleeve 15 mounted on a throttle shaft 16 having a bearing at its opposite ends in the wall of the shell and having a throttle lever 17 secured to one end outside of the shell as a means 75 for operating the throttle valve or throttle in a manner that will be readily understood.

A fuel valve actuator 18 is supported by the throttle valve in position to operate the fuel inlet or needle valve 11, in the form herein 80 shown, this actuator being in the form of a cam plate having its end in sliding contact with a roller in a groove in the outer surface of the bottom of the cup 13. In order to provide for a proper adjustment of the actuator for idling purposes, or otherwise, an adjusting screw 19 is extended laterally through the sleeve 15 and shaft 16 and an actuator stem 20 extends through a hole formed lengthwise in said screw, the lower edge of the actuator resting upon the screw. By 85 this means the position of the actuator may be fixed to provide for the admission of such amount of combustible fluid as may be desired. A set screw 26 projects into a hole extending lengthwise into the shaft 16 from one end thereof, 90 said screw being threaded just underneath a knurled head thereon for engagement with the screw threaded mouth of said hole. The rest of the screw is smooth to its inner end which engages with a shoe pressed against the stem 20 of 95 the actuator for the purpose of retaining the parts in place. 100

A priming lever 21 is pivotally mounted in a notch in the end of the shell, one arm of said lever underlying the end of the stem 20 for 105 operation thereof and the other arm of said lever being adapted for connection with any suitable device for operation of the priming mechanism, it being noted that when the lever 21 is operated, the needle valve 11 will be opened to 110 supply a quantity of combustible fluid to the interior of the shell and without increasing the amount of air entering the shell, said air being substantially completely shut off at this time by reason of the throttle being closed. 115

It is often desirable to enrich the explosive mixture for the performance of heavy duty by an engine, particularly when driving an automobile, and under conditions requiring quick action, and I have provided means in my im- 120

proved carburetor, illustrated and described herein, for effecting this result. The fuel valve actuator 18 is so curved for the greater portion of its length, and to the point *a*, as to properly control the gas inlet or needle valve 11 to admit the necessary amount of fluid in proportion to the air to meet the ordinary requirement. From the point *a* I have increased the radius of the curve from that which would be required for light duty and thereby provide a power accelerator which increases the degree of opening movement of the needle valve in proportion to the amount of opening movement of the throttle valve 14, thereby enriching the explosive mixture.

For the purpose of explanation let it be assumed that the carburetor is employed in an automobile used only for light duty. In this case the actuator would be of a length extending substantially to the point *a* or, if longer, from the point *a*, the actuator would be formed on a curve denoted by the dotted line 22. In the present instance I have increased the radius of the curve to an extent denoted by the dotted line and the full line at the edge of the actuator, this portion of the actuator being the power accelerator 23 which operates as follows: Under ordinary running conditions requiring comparatively little power, as on down grades, level stretches, or light upgrades, the throttle will be opened to effect contact of the actuator 18 and priming cup 13 from the starting point on the actuator approximately to the point *a*. Under these conditions if the throttle be opened more, the increase in proportion of the combustible fluid or fuel over the air would hamper the action of the engine, either slowing it down or stopping it.

When equipped with my power accelerator the running conditions above described would be the same. If, however, a requirement suddenly develops for the exercise of greater power by the engine, the throttle is opened to contact the actuator 18 with the cup 13 beyond the point *a*, thereby at once increasing the richness of the explosive mixture and enabling the engine instantly to meet the added requirements and perform the extra heavy duty required, this without substantial extra effort on the part of the driver and without a different effort than that required to drive the engine under ordinary conditions.

To effect the result just hereinbefore described, it is simply necessary to make the actuator 18 enough longer than would otherwise be required and increase the radius of this portion, such extra length being that from the point *a* to that end opposite the starting point, and in order not to increase the size of the shell 3, I form an opening 24 through the shell wall and cover this opening by a thin plate 25, and as shown in Figure 1 of the drawing.

As a support for the priming cup 13, I provide a spider the arms 27 of which are secured in openings in a venturi 28 and in the shell 3, and as shown in Figures 1 and 3. These arms extend radially from a hub 29 having a hole therethrough to fit the cup 13 in a manner to permit easy sliding movement of said cup in the hub. The opening through the venturi is preferably of the least diameter about opposite the mouth of the priming cup 13, gradually taper-

ing from this point to a greater dimension inwardly.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim:

1. A carburetor including a shell having a combustible fluid inlet, a valve to control flow through said inlet, a throttle located within the shell, a priming cup operatively connected with said valve and surrounding the outlet tip of said inlet, a spider comprising arms extending radially from the walls of the shell and terminating in a socket to receive said cup to support it in its movement with said valve, a valve actuator mounted on said throttle on the inner face thereof, and operatively connected with said valve for operation of the latter, means for adjusting the position of said actuator with respect to said valve and including a screw extending through the throttle and accessible at the end of the shell, and means for operating said actuator.

2. A carburetor including a shell having a combustible fluid inlet, a valve to control flow through said inlet, a throttle, a priming cup operatively connected with said valve and surrounding the outlet tip of said inlet, a spider comprising arms extending radially from the walls of the shell and terminating in a socket to receive said cup to support it in its movement with said valve, a valve actuator mounted on said throttle and operatively connected with said valve for operation of the latter, a stem projecting from said actuator, an adjusting screw engaged with said stem and accessible at the end of the shell for adjusting the position of the actuator with respect to the valve, and means for operating the actuator.

3. A carburetor including a shell having a combustible fluid inlet, a valve to control flow through said inlet, a throttle, a priming cup operatively connected with said valve and surrounding the outlet tip of said inlet, a spider comprising arms extending radially from the walls of the shell and terminating in a socket to receive said cup to support it in its movement with said valve, a valve actuator mounted on said throttle and operatively connected with said valve for operation of the latter, an adjusting screw engaged with said throttle and having a hole therethrough, a stem projecting from said actuator through said hole and out at the end thereof, and means engageable with the end of said stem for the operation of said actuator.

4. A carburetor including a shell having a combustible fluid inlet, a valve to control flow through said inlet, a priming cup borne by said valve and surrounding the outlet tip of said inlet, a spider comprising arms extending radially from the walls of the shell and terminating in a socket to receive said cup and support it in its movement with said valve, and means for operating said valve.

GRANT HAMMOND.
